UNITED STATES PATENT OFFICE

FRIEDRICH LEISER, OF BERLIN-CHARLOTTENBURG, GERMANY

ROTARY STOP DEVICE FOR SCREENING OFF SECONDARY X-RAYS

Application filed May 2, 1927, Serial No. 188,357, and in Germany May 5, 1926.

This invention relates to a stop device for screening off the secondary X-rays by means of a device which is rotatable about an axis. In the known stops of this type the focus of the tube is positioned above the axis of rotation of the stop, while the rotary motion of the latter is obtained by means of a drive acting upon a toothed annulus at the periphery of the stop frame, whereby the angular speed of the stop is reduced. This arrangement is accompanied by the disadvantage of an increase in the time of exposure and in that a portion of the effective rays becomes destroyed, thus further increasing the time necessary for exposure.

These disadvantages are removed by the invention according to which the axis of rotation of the stop is arranged parallel with the central ray of the Roentgen tube. In this way any desired speed of rotation of the stop is rendered possible, so that exposures can be taken which do not exceed the time of one half of a second, such as they are required when taking Roentgen photographs of the lungs, heart, stomach, the intestines, and so on.

By the provision, according to the invention, of strips of hard lead arranged to be rotatable around their axes it is possible better to exclude the effects of straying secondary rays, so that the image on the fluorescent screen appears much clearer while the Roentgen picture shows better contrasts as will be hereinafter more readily apparent. The employment of strips of lead for the exclusion of the secondary rays is known per se but in the known arrangements the said strips are arranged parallel to each other and so as to be moved only to and fro about their axes.

The accompanying drawings illustrate the invention by way of an example.

Fig. 1 is a vertical section taken on lines 1-1 of Figure 4,

Fig. 2 is a plan view of the device,

Fig. 3 is an enlarged fragmentary section taken on the line 3-3 of Figure 4, and

Fig. 4 is a horizontal section taken on the line 4-4 of Figure 3.

In these drawings 1 is an annular frame preferably made of band iron and provided

with a number (twelve for example) of leaden blades 2 arranged spoke fashion and turnable about their pins 3, while at their opposite inner ends they are each provided with a gear or pinion 5'. All of these gears or pinions 5' are arranged in engagement with a ring gear or pinion 5 on a shaft 4 of the device in such a manner, that each rotation of the frame 1 will cause each of the blades to make a complete half turn about its longitudinal axis; whereby the edge of each blade, being about 1 mm. in thickness, will be successively presented in a vertical position opposite the screen (shown dotted at 7) at about the centre of the same as is clearly indicated by the position of the blade 6.

The shaft 4 of the frame 1 is driven at high speed as by means of an electric motor 8. A protecting screen for the patient under treatment is shown at 9 in Fig. 2.

In the operation of the device as thus constructed and arranged, the focus of the X-ray tube or anti-cathode (not shown) is approximately at the center, or slightly above the center of the upper vertical radius of the circular frame 1, or midway between the axis of the frame 1 and the highest point on its periphery, as is clearly indicated by the position of the fluorescent screen or plate 7. The radially disposed leaden members or spokes 2 are turned on their axes, through the medium of the cooperative gears or pinions 5 and 5' for exactly 180° during each full revolution of the frame 1, and as each arrive at vertical position at the upper side of the frame 1, they are positioned in edgewise relation to the X-ray tube or anti-cathode and the screen 7 at the approximate centers of the latter, so that the primary or central rays from the tube or anti-cathode pass unobstructed to the plate or screen 7. However, in the vertical position of one of the leaden members or spokes 2, the oppositely disposed of the other several members or spokes 2 are being continuously turned to varying angular positions with respect thereto, and with respect to each other by reason of the continued rotation of the frame 1, and are thus presenting to secondary or "straying" rays, from the X-ray tube or anti-cathode, appre-

ciable areas of their side faces, with the result that these latter rays are absorbed.

By reason of the absorption of the secondary or "straying" rays aforesaid, the obtained picture on the fluorescent screen or plate 7 will be much clearer than it has hitherto been possible to produce, and furthermore, the picture, when in the form of an X-ray diagram, will show greater and more marked contrasts for the same reason. It is also to be noted that by driving the frame 1 at higher speeds, the absorption of the secondary or "straying" rays is accomplished in a manner that there is substantially no impairment effects, such as, for instance, the stretching of the resultant picture out of shape or proportion, such as is often the case in the heretofore known practice.

The blades 2 may consist of hard lead preferably of an appreciable transverse area or width, and may, or may not have a strengthening frame of a more solid material which, however, must be penetrable to the X-rays. Thus it may consist of a suitable metal; in some cases a tough lead alloy or other composition will serve the purpose and which may contain about 95 to 96 per cent of lead for example.

As shown in Figures 3 and 4, the inner ends of the radial blades 2 are journaled in a hub portion 10 and have the beveled gears 5' keyed thereon inwardly of the hub. One end of the hub 10 is closed by a wall 10', which is engaged at the center of its inner side by one end of the driving shaft 4.

Mounted on the shaft 4, for rotation independently thereof, is a sleeve 11 which has a beveled gear 5 at one end and disposed within the open end of the hub 10 for meshing engagement with the beveled gears 5' aforesaid, and a gear 12 at its other end disposed in mesh with a companion gear keyed on a countershaft 14. This countershaft 14 is journaled in a bearing 15' disposed alongside a similar bearing 15 for the driving shaft 4, so as to extend parallel to the latter substantially as shown. Keyed on the driving shaft 4, beyond the outer side of the gear 12, is another gear 16, which is arranged in mesh with a companion gear 17 keyed on the countershaft 14.

Now, with the motor 8 coupled to the free end of the driving shaft 4 and connected to a current supply line (not shown), the frame 1 will be rotated with the shaft 4, when the gear 16 on the latter will drive the countershaft 14 through the intermeshing gear 17. Upon rotation of the countershaft 14, the gear 13 carried thereby will drive the sleeve 11 through the intermeshing gear 12. When the beveled gear 5 will also be rotated and will transmit motion to the beveled gears 5' for the rotation of the spokes 3 as aforesaid.

What I claim is:

1. A rotary stop for screening off second-

ary X-rays comprising an open frame, strips of screening material spaced radially within said frame and rotatable relatively thereto and to each other, and means for rotating said frame and said strips simultaneously. 70

2. A rotary stop device for screening off secondary X-rays, comprising a circumferential ring member, a turning axle, individually turnable blades between the said ring member and the said turning axle, and means to automatically turn each of the blades one-half a revolution around its longitudinal axis during one rotation of the stop device. 75

3. A rotary stop device for screening off secondary X-rays, comprising a circumferential ring member, a turning axle, individually turnable blades between the said ring member and the said turning axle, a pinion at the inner end of each of the said blades in engagement with an annulus on the turning axle, and means for rotating said axle to cause a simultaneous relative rotation of said ring member and said blades. 80

4. A rotary stop device for screening off secondary X-rays directed toward a Roentgen screen comprising a turning axle, radial strips of lead turnable about their longitudinal axes and mounted spoke-fashion upon the turning axle, and means to automatically turn each of the strips one-half a revolution around its longitudinal axis during one rotation of the stop device. 85

5. A rotary stop device for screening off secondary X-rays, comprising an axle, a circular frame mounted in concentric relation to said axle, leaden strips journaled radially of said axle and frame, means for rotating said axle and frame, and means operated from said axle for simultaneously rotating said leaden strips. 90

6. A rotary stop device for screening off secondary X-rays, comprising an axle mounted parallel to the path of the central ray emanating from a Roentgen tube, a circular frame mounted in concentric relation to said axle, leaden strips journaled radially of said axle and frame, means for rotating said axle and frame, and means operated from said axle for simultaneously rotating said leaden strips through an angle of 180° for each complete revolution of said axle and frame. 110

7. A rotary stop device for screening off secondary X-rays, comprising an annular frame, a power shaft, a hub portion fixed to said shaft, strips of screening material spaced radially within said frame and journaled at the opposite ends in the frame and in the hub portion, and means for rotating said strips simultaneously with the rotation of said frame and said shaft. 120

8. A rotary stop for screening off secondary X-rays, comprising an annular member, a rotatable shaft, a hub mounted on said 125

shaft, individually turnable blades of screenable material disposed between said annular member and said hub, a pinion at the inner end of each of said blades, means for imparting motion to said shaft for the rotation of said annular member and said hub and means operable from said shaft for causing a simultaneous relative rotation of said blades through said pinions.

9. A rotary stop for screening off secondary X-rays, comprising an annular member, a rotatable shaft, a hub mounted on said shaft, individual turnable blades of screenable material disposed between said annular member and said hub, a pinion at the inner end of said blades and within said hub, power means for imparting motion to said shaft for the rotation of said annular member and said hub, and means operable from said shaft for causing the simultaneous relative rotation of said blades through said pinions.

In testimony whereof I affix my signature.

25 FRIEDRICH LEISER.
